LIFTING JACK FOR MOTOR VEHICLES

Carl Schmitt, Leipzig, Germany; vested in the
Alien Property CustodianApplication January 6, 1941, Serial No. 373,239½
In Germany May 5, 1939

2 Claims. (Cl. 254—86)

This invention relates to a telescopic and fluid-operated lifting jack for motor vehicles.

According to the invention, the vehicle is provided at a suitable point, preferably under the hood at the dashboard, with a liquid-containing receptacle and a pump, or with a pump for producing compressed air, whence conduits extend to supply points suitably arranged on both sides of the vehicle and are adapted to cooperate with the detachable telescopic lifting jack the filling of which with a pressure medium, as liquid or air, is controlled from the driver's seat.

The invention is illustrated by way of example in the accompanying drawing showing an oil-operated hydraulic jack.

Figure 1 is a longitudinal section of a telescopic jack according to the invention in operating condition;

Fig. 2, a longitudinal section thereof in inoperative position;

Fig. 3 is a side elevation of a plug adapted to close an upper supply opening in the jack.

Fig. 4 is a view partly in section and partly in elevation of the cap to close the opening in the fluid supply means for the jack.

Fig. 5 is a detailed sectional view on the line 5—5 of Fig. 1 and

Fig. 6 is a view similar to Fig. 5 but showing the parts in different relative position.

The lifting jack comprises telescopic tube members 1 correspondingly sealed relatively to one another and provided with passages 2 for liquid or air. The base member 3 is fitted with a ball and socket joint 4 so as to be universally movable and permit adaptation of the jack to unevennesses of the ground. With the aid of a screw member 5 the base 3 can be screwed into the lowermost tubular member to lengthen or shorten the jack as required. In the example shown holes are provided in the ball of the joint for moving the screw member by means of a pin, though other arrangements may be made of course. The jack is acted upon by the pressure medium, as liquid or air, in known manner and thus placed in supporting position to lift the vehicle. The jack is detachably connected to the vehicle by means of a U-shaped support 16 in which a supply outlet or mouthpiece is rotatably disposed. A cock plug 17 is arranged in a casing 10 and is provided with an outer case 9 rotatable on the plug 17 and held in position on the plug 17 by a spring 11. The case 9 supports a conical member 8 to which the jack is attached with its top 1 which for this purpose is fitted with a conical sleeve or socket 6 having a passage 7 for liquid or air. The cock

plug 17 possesses a channel 18 extending along its longitudinal axis and also a channel 19 branching off from the channel 18 in vertical direction thereto, and the end of the plug 17 where the channel 18 opens can be connected, for instance by a hose coupling, etc., to a conduit 12 coming from the pump. The conical member 8 is provided with a channel 20 extending vertically toward the channel 18, so that at a 90° rotation of the case 9 about the plug 17 (from the horizontal to the vertical position of the member 8) the channels 18, 19 will be in communication with the radial channel 20 and permit passage of the pressure medium which enters the jack through the passage 7 of the sleeve 6. This rotation is effected by the jack attached with its conical sleeve 6 to the conical member 8. When the case 9 is turned back 90° at the removal of the jack, which takes place under the influence of spring 11 communication between the channels 18, 19 and 20 ceases and the channel 19 is shut off by the wall of the case 9.

When attached to the member 8 the jack is secured in vertical position by the flanges 21 which engage behind angular members 13 of the casing 10.

The support 16 is laterally recessed for the passage of the ends of the valve cone and of the connecting means for the conduit 12. The plug 17 is provided with a screw headed head 22 adapted to be received in the internally screw threaded cap 23 rotatably mounted on the end of conduit 12.

When the jack is detached from the member 8 the opening thereof is closed by a threaded plug 14 shown in Fig. 3 to prevent the entrance of dirt and the opening in the conical member 8 may be closed by the cap 15 shown in Fig. 4.

To apply the jack, it is held horizontally and the conical socket 6 is placed over the conical member 8 which member is normally in a horizontal position. The jack is then turned down to the vertical position as shown in Fig. 1 which places passage 19 in the cock plug 17 in communication with passage 20 in member 9. In this movement the weight of the jack is sufficient to overcome any force exerted by the spring 11 and during the downward movement the inwardly projecting portions of the members 13 are brought under the projections 21. The screw 5 may then be adjusted if desired so that the base 3 is firmly seated on the ground. The nozzle cap 23 is placed over the plug 22 and air supplied to the interior of the jack from a pump or reservoir, not shown.

What is claimed is:

1. A fluid-operated telescope lifting jack at-

tachable to motor vehicles, comprising a body portion of telescopic tubes fitted with passages for a pressure medium, a universally movable ground engaging base member attached to said tubes, a support on the vehicle frame for attaching said body portion thereto, a mouthpiece rotatably disposed on said support, a cock plug arranged in a casing possessing angular engaging members, said mouthpiece comprising a rotatable outer case for said plug, a spring for holding said outer case in position on said plug, a conical member supported by said outer case for attaching the top portion of the jack thereto, a conical sleeve with a passage for a pressure medium in said top portion, an axial channel and a second channel branching off from said first channel in vertical direction thereto in said cock plug, a supply conduit connectible to the end of said plug where said first channel opens, a third channel provided in said conical member and extending vertically toward said first channel, said channels being in communication when the jack is turned 90° into operative position to permit the passage of a pressure medium and out of communication at the return motion of the jack, flanges on said body portion engaging behind said angular members of said casing to secure the jack in attached position and a thread-

ed plug for closing the opening of said conical member after removal of the jack.

2. A fluid operated lifting jack attachable to a motor vehicle, comprising a body portion of telescopic tubes having passages for a pressure medium, a universally movable ground engaging base member attached to said tubes, a support on said vehicle frame for attaching said body portion thereto, a plug fixed to said support, a rotatable casing on said plug and having a conical member thereon said casing and member being formed with communicating radial passages a spring between said casing and support for holding said casing on said plug and tending to rotate said casing to position said passages inclined to the vertical, said plug being formed with passages communicated with said radial passages when said radial passages are vertical, means for supplying fluid under pressure to the passages in said plug and the top of said body portion being provided with a conical socket, adapted to receive said conical member and said socket having a passage adapted to communicate with said radial passages when the jack is applied to said conical member.

CARL SCHMITT.
